UNITED STATES PATENT OFFICE.

JOSEPH J. CYGAN, OF THOMPSONVILLE, CONNECTICUT.

SILVER CHEST.

Application filed April 7, 1925. Serial No. 21,302.

To all whom it may concern:

Be it known that I, JOSEPH J. CYGAN, a citizen of the United States, residing at Thompsonville, in the county of Hartford and State of Connecticut, have invented new and useful Improvements in Silver Chests, of which the following is a specification.

This invention relates to improvements 10 in silver chests which comprises an inclosing casing, a plurality of drawers that may be readily withdrawn from the inclosing casing with a single operation and may be returned to the casing by a single 15 operation.

The invention broadly comprises an inclosing casing having an upper part which is formed with a fixed compartment that is closed by a cover or lid which is hinged to 20 the casing and below the upper compartment are located a plurality of drawers that are arranged one above the other and so constructed that when the lowermost one is withdrawn it operates to pull out the one 25 immediately above and this in turn withdraws the one above that. Each of the drawers have a rod attached thereto at their opposite ends and located on these rods are supporting clips or ear pieces which are 30 formed with openings to receive the rod, whereby the drawers are supported by the rods.

Referring to the drawings:

Fig. 1 is a front elevational view showing 35 the inclosing casing with the several drawers therein, and the upper lid closed.

Fig. 2 is a partial transverse sectional view on the line 2—2 of Fig. 3 showing 40 two of the rods with the supporting clips and the inclined arrangement of the ends of the drawers, and

Fig. 3 is a view illustrating the three 45 drawers extended and the lid of the upper compartment raised.

Referring to the drawings in detail:

1 designates the inclosing casing as a 50 whole, having the end pieces 2 and 3, the bottom piece 4 the lid 5 and the back portion 6. The front part of the casing is left open to receive the drawers 7, 8, and 9; the upper front portion of the casing being closed as indicated at 10. Secured in the front and back pieces 10 and 11 are the rods 12 which are located between the bottom of the upper compartment 13 and the end portions 2 and 3 as shown in Figs. 1

and 2. It should be observed that the end walls 14 of the upper compartment 13 are inclined as shown clearly in Fig. 1. The end walls 15, 16, and 17 of the drawers 7, 69 8 and 9 are also inclined and rods 18, and 19 are secured to the drawers 8 and 9 as shown. Attached to the opposite ends of the drawers 7, 8, and 9 are the inverted U-shaped ear pieces 20, 21, 65 and 22 by means of the screws indicated at 23. These ear pieces are formed with an opening at their upper ends to receive the rods 12, 18, and 19. These ear pieces it will be noticed are located in the inner ends 70 of the drawers, that is to say, adjacent the pieces 24, 25, and 26.

It will be observed that when the three drawers are pulled outward into the position shown in Fig. 3, that the contents of 75 the same may be observed at the same time, and the different articles that are to be placed in the different drawers may be readily placed therein.

The operation may be described as follows: Assume that the three drawers are pushed into the casing 1, in their closed position. The operator, by means of the knob 27, pulls outward on the lowermost drawer 7. The ear piece 20 will slide on 80 the rod 19 of the drawer directly above until it strikes the front piece 28 causing this drawer to move outward into the position shown. When it reaches this outermost position the ear 21 will slide on the rod 90 18, until it engages the part 30 which will cause the ear 22 to slide on the rod 12 into outward position shown. The front part 10 of the casing will then operate as a stop for all of the drawers. In closing the 95 drawers, the reverse operation takes place. The drawer 7 is pushed inward until the part 20, which slides on the rods 19, engages the part 25 causing the drawer 8 to move inward by sliding on the rod 18 when 100 the ear 21 will engage the part 26 causing the drawer 9 to slide inward on the rods 12.

It will therefore be seen that I have provided silver chests in which the drawers 105 may be readily opened and closed. The lid 5 is closed by means of the latch 31. It will be observed that the ends of the drawers 7, 8, and 9 are inclined to provide spacing or room to receive the rods 18 and 19, 110 and also to receive the ear pieces 20, 21, and 22.

What I claim is:

1. An inclosing casing having its front wall formed with an opening in the lower portion of the same, rods attached to the upper parts of the casing for slidably supporting a drawer next below the rods; said drawer having rods attached to its opposite ends for slidably supporting a drawer immediately below, and this immediately located drawer also having rods attached to its opposite ends for slidably supporting the lowermost drawer of the casing, ear pieces on each of the drawers for sliding on the said rods and engaging the drawer above, the construction and arrangement being such that when the lowermost drawer is pulled outward it operates to withdraw all of the drawers above.

2. An inclosing casing having its front wall formed with an opening, a fixed compartment in the upper end of the casing, the ends of the compartment being inclined to provide a space between the ends of the casing and the fixed compartment, rods secured at the ends of the fixed compartment in said space, a drawer, ears attached to the drawer and slidably mounted on the rods for supporting a drawer in the opening, said drawer having its opposite ends inclined, rods attached to the front and rear pieces of the drawer, ears mounted thereon and attached to a drawer immediately below the first mentioned drawer whereby when the drawers are pushed inward or outward the ears will slide on the rods and serve to

move the drawer immediately above and either into or out of the casing.

3. In a cabinet for the purpose described, a plurality of slidable drawers attached thereto, the ends of each of the drawers being inclined, rods located in the space between the lower ends of the inclined end pieces of the drawers and the vertical end walls of the cabinet, rods attached to the front and rear walls of each of the drawers, ears attached to the ends of the drawers and slidable on the rods which will engage the front and rear walls of the drawers, whereby when the drawers are moved inward or outward of the cabinet they will slide on the rods until they engage said walls to move the drawers either inward or outward, as described.

4. A cabinet structure for the purpose described having end and rear walls, the front wall being formed with an opening for receiving a plurality of movable drawers, a fixed compartment in the upper end of the cabinet, a cover or lid for this compartment, the opposite ends of the fixed compartment and the movable drawers being inclined, drawer supporting rods located at the ends of the fixed compartment and on the movable drawers, and near the bottoms of the same, ear pieces attached to the drawers and slidable on the rods, whereby when the lowermost movable drawer is operated the other movable drawers are operated one from the other.

JOSEPH J. CYGAN.
